US00D712809S

(12) **United States Design Patent**
Kloos

(10) **Patent No.:** **US D712,809 S**
(45) **Date of Patent:** **** Sep. 9, 2014**

(54) **DISK BRAKE FRICTION LINING
RETAINING DEVICE**

(71) Applicant: **WABCO GmbH**, Hannover (DE)

(72) Inventor: **Eugen Kloos**, Bensheim (DE)

(73) Assignee: **WABCO GmbH**, Hannover (DE)

(**) Term: **14 Years**

(21) Appl. No.: **29/461,996**

(22) Filed: **Jul. 30, 2013**

(30) **Foreign Application Priority Data**

Feb. 15, 2013 (EM) 001361034-0001

(57) **CLAIM**

The ornamental design for a disk brake friction lining retaining device, as shown and described.

DESCRIPTION

FIG. 1 is a top, front, left side perspective view of a disk brake friction lining retaining device showing the new design; FIG. 2 is a top plan view thereof;

FIG. 3 is a rear elevational view thereof, the front elevational view being a mirror image;

FIG. 4 is a right side elevational view thereof, the left side elevational view being a mirror image; and,

FIG. 5 is a bottom plan view thereof.

The broken lines are for the purpose of illustrating environmental structure and form no part of the claimed design.

1 Claim, 3 Drawing Sheets

FIG. 2

FIG. 3

FIG. 4

FIG. 5
